DIMENSIONALLY STABLE ANODE

James Wesley Bess, Sr., Painesville, Ohio, Oronzio de Nora, Milan, Italy, Richard E. Loftfield, Chardon, Ohio, and Giovanni Trisoglio, Milan, Italy, assignors to Electronor Corporation, Chiasso, Switzerland

Filed Aug. 8, 1969, Ser. No. 18,599

Term of patent 14 years

Int. Cl. D13—99

U.S. Cl. D26—1

FIG. 1 is a perspective view of the dimensionally stable anode;

FIG. 2 is a plan view.

The cross hatching on the bottom face of the anode is intended to represent foraminous metal, continuous throughout the entire face.

We claim:

The ornamental design for a dimensionally stable anode, as shown and described.
